E. M. McMILLAN,
FLOAT VALVE FOR STEAM BOILERS,
APPLICATION FILED FEB. 27, 1918.

1,354,619.

Patented Oct. 5, 1920.

UNITED STATES PATENT OFFICE.

EPHRAIM M. McMILLAN, OF TAFT, CALIFORNIA.

FLOAT-VALVE FOR STEAM-BOILERS.

1,354,619.

Specification of Letters Patent.

Patented Oct. 5, 1920.

Application filed February 27, 1918. Serial No. 219,431.

To all whom it may concern:

Be it known that I, EPHRAIM M. McMILLAN, a citizen of the United States, residing at Taft, in the county of Kern and State of California, have invented certain new and useful Improvements in Float-Valves for Steam-Boilers; and I do hereby declare the following to be a full, clear, and exact description of the invention, such as will enable others skilled in the art to which it appertains to make and use the same.

My invention relates to improvements in float valves for steam boilers whereby the supply of steam which actuates the pump which forces the water into the boiler may be controlled automatically by the operation of the said float.

A further object of this invention is to provide a float in communication with the water supply and steam supply whereby the pressure may be equalized on both sides of the float to automatically open and close the communication between the steam supply and pump and automatically operate this pump to force water into the boiler, and automatically close the said pump when the water line in the boiler is reached.

A still further object of this invention is to provide a float valve of this character, which will be simple, practical and comparatively inexpensive in construction and one that can be manufactured and sold at a low cost.

With these and other objects in view, the invention consists in the novel combination and arrangement of parts hereinafter more fully described and set forth in the claim hereto appended.

In the drawing:

Figure 1 is a vertical longitudinal sectional view of the float valve showing the same in use.

Fig. 2 is an enlarged vertical sectional view illustrating more clearly the construction of the interior of the valve casing and valve.

Fig. 3 is a transverse sectional view taken on the line 3—3 of Fig. 2.

Like numerals of reference designate corresponding parts in all the figures of the drawing.

Referring to the drawing, the numeral 5 indicates a boiler having connected thereto and communicating therewith a supply pipe 6. The supply pipe 6 is connected to a suitable pump 7 which pump is in communica-

tion with a water supply tank 8 through the medium of a pipe 9. When the pump 7 is actuated water is forced from the supply tank 8 through the pipe 9 and pump 7 and 60 through the pipe 6 into the boiler 5 until it reaches a predetermined water level therein designated A in Fig. 1. A steam supply pipe 10 has one end connected to the boiler as at 11 above the water line and 65 its opposite end is connected to and communicates with the pump 7 as at 12.

A vertical branch pipe 13 has one end connected to and communicating with the steam supply pipe 10 and has secured to its 70 upper end a steam gage 14. A horizontal branch pipe 15 extends from said pipe 13 and has its free terminal extended downwardly and is in open communication with the reduced end or sleeve 17 of a valve casing 18. The reduced portion or sleeve 17 of the valve casing is in open communication with the steam supply pipe 10 which extends therethrough and also in communication with this pipe through the medium 80 of the branch pipes 13, 15 and 16 respectively.

The casing 18 has secured to its bottom wall a pipe 19 connecting the casing with the water space of the boiler. A sliding 85 float 20 is located within the casing 18. The float 20 has secured to its upper side a vertical hollow tube 21 and this tube 21 is adapted to close the communication between the steam supply pipe 10 and the reduced portion 17 of the casing. The tube 21 is also provided with a plurality of relatively spaced openings 22 at diametrically opposite points and at right angles to the ends of the portions of the steam supply 90 pipe 10. It will be apparent that when the pump is actuated that the float is at the lower portion of the casing 18, the water is then forced into the boiler 5 until it reaches a predetermined level, which when seeking 100 its level will raise the float and the tube 21 upwardly closing the communication of the steam supply and automatically stopping the pump and steam will then pass up through the branch pipe 13 through the 105 branch pipe 15 and down into the upper end of the reduced portion 17 of the casing and out through the perforations in the tube 21 and thus the pressure on the float will be equalized. The apertures 22 in the hollow tube 21 render the float 20 subject to the boiler pressure at all times,

The casing 18 is provided with a suitable steam and water gage 23 which gage is controlled with a suitable turn valve 24. The casing is also provided with a plurality of 5 outlet cocks 25 controlled by suitable valves 26. These cocks provide means whereby the casing may be drained.

In use:

It will be understood that the device is 10 automatic. When the water in the boiler drops to a predetermined level the float will drop to the bottom of the casing 18, thus permitting the steam in the upper portion of the boiler to pass through the pipe 10 down into the pump 7 and actuate said 15 pump and the pump then forces the water from the supply tank 8 into the boiler 5. The water rising to a certain level in this boiler forces the float 20 upwardly and 20 moves the tube 21 into such a position that the supply of steam through the pipe 10 is cut off, thus directing the steam up through the branch pipes 13, 15 and 16, respectively, into the upper end of the reduced portion 17 of the casing 18 and it 25 then passes downwardly through the tube 21 and out through the openings 22 upon the float, equalizing the pressure. It will be apparent that the instant the water starts to 30 fall the float will drop toward the bottom of the casing, opening the communication

of the steam supply pipe to the pump to actuate the pump again to furnish a new supply of water to the boiler.

Having thus described my invention what 35 I claim is:

A valve for steam boilers comprising a float chamber, a reduced neck formed on said chamber and having oppositely disposed ports adjacent its upper end, a water 40 pipe connecting said chamber to a boiler, a steam pipe connected to one of the ports and to the boiler, a by-pass steam pipe connected to the end of the neck and to the steam pipe, a second steam pipe connected 45 to the other port, a steam actuated pump connected to the second named steam pipe and having communication with a water source and with the boiler, a float in said chamber, and a tube formed on the float and 50 in engagement with the wall of the neck and adapted to stop the flow of steam between said steam pipes when said float is in its uppermost position, said tube having openings to permit steam from the by-pass pipe 55 to enter the chamber above the float.

In testimony whereof I affix my signature in presence of two witnesses.

EPHRAIM M. McMILLAN.

Witnesses:

GEORGE T. WHITE,
E. W. CRAGHILL.
